US00D958148S

(12) **United States Design Patent** (10) **Patent No.:** **US D958,148 S**
Chen et al. (45) **Date of Patent:** **** Jul. 19, 2022**

(54) **DISPLAY STAND**

(71) Applicant: **SHENZHEN BESTQI INNOVATION TECHNOLOGY CO., LTD**, Shenzhen (CN)

(72) Inventors: **Huasheng Chen**, Shenzhen (CN); **Changgan Shen**, Shenzhen (CN)

(73) Assignee: **SHENZHEN BESTQI INNOVATION TECHNOLOGY CO., LTD**, Shenzhen (CN)

(**) Term: **15 Years**

(21) Appl. No.: **29/783,415**

(22) Filed: **May 13, 2021**

(51) LOC (13) Cl. **14-02**

(52) U.S. Cl.

USPC **D14/451**; D14/447

CLAIM

The ornamental design for a display stand, as shown and described.

DESCRIPTION

FIG. 1 is a perspective view of a display stand showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1; and,

FIG. 11 is an enlarged view of portion 11 shown in FIG. 2. The broken lines in the drawings depict portions of the display stand that form no part of the claimed design.

1 Claim, 11 Drawing Sheets
